UNITED STATES PATENT OFFICE

165,605

TOY STOVE OR SIMILAR ARTICLE

Mark Page, East Orange, N. J.

Application June 24, 1950, Serial No. 10,726

Term of patent 14 years

(Cl. D34—15)

To all whom it may concern:

Be it known that I, Mark Page, a citizen of the United States, residing in the city of East Orange, county of Essex and State of New Jersey, have invented a new, original and ornamental Design for a Toy Stove, or Similar Article; of which the following is a specification, reference being had to the accompanying drawing, forming a part hereof.

Inasmuch as the back of the stove is plain, no figure depicting the same is included in the drawing.

I claim:

The ornamental design for a toy stove, or similar article, as shown and described.
